(57) **CLAIM**

The ornamental design for a hybrid paystation, as shown and described.

DESCRIPTION

FIG. 1 is a perspective view of a hybrid paystation showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof;

FIG. 9 is a rear perspective view thereof; and,

FIG. 10 is a rear perspective view thereof.

The broken lines present in the drawings are included for the purpose of illustrating portions of the article which form no part of the claimed design.
